UNITED STATES PATENT OFFICE.

EDWARD GREEN, OF WAKEFIELD, ENGLAND.

HEATING APPARATUS.

SPECIFICATION forming part of Letters Patent No. 610,134, dated August 30, 1898.

Application filed December 20, 1897. Serial No. 662,672. (No model.) Patented in England August 3, 1897, No. 18,086.

To all whom it may concern:

Be it known that I, EDWARD GREEN, baronet, a subject of the Queen of Great Britain, residing at Wakefield, Yorkshire, England, have invented certain new and useful Improvements in or Connected with Heating Apparatus, (patented in Great Britain, No. 18,086, August 3, 1897,) of which the following is a specification.

- 10 This invention has for its object arranging valves within the boxes or entry and exit pipes of a fuel-economizer in such manner that all the tubes may be simultaneously charged with the supply-water or the rods be moved so that the valves may close against the flow of the supply-water except to the first or to the combined first and second vertical tubes of a row of such tubes, the valves being brought against partitions in the boxes or 15 pipes by a push-in or draw-out motion imparted to the rods by screw or other means from outside the boxes or pipes, the valves for the time being located permanently or temporarily, according to circumstances and 20 as desired.

The boxes or supply-pipes, with my shiftable valve and rod arrangement within them and horizontally both at top and bottom, may have vertical tubes—say six or more—and 25 constitute a set ready for being fitted into the flueway of a furnace for heating the water in such boxes or pipes and tubes previous to its use—say for the heating of feed-water for a boiler—or if the boxes or the pipes containing the valves and rods be provided with side 30 branches other boxes or pipes without valves and rods, but having sockets with other vertical tubes, can be secured to them to constitute series or nests of vertical tubes up or 35 down or through which the water can flow to the series or nests of tubes, with their transversely-arranged boxes or pipes, in order that the transverse branch box or pipe of one row of vertical tubes or two of such rows of vertical 40 tubes may be collectively charged with the supply-water, or the next row or the next two rows and its or their respective transverse boxes or pipes by the arrangement of the valves and rods in the supply boxes or 45 pipes, the next adjoining row or next two adjoining rows of vertical tubes, with their boxes or pipes, can be collectively charged

with the supply-water before the water flows in the reverse direction down or up the next row, series, or nests of vertical tubes and 50 their respective transverse boxes or pipes, or by shifting the valves and rod of one box or pipe to the requisite position with relation to the position of the valves and rod of the other box or pipe in or to which the transverse boxes 55 or pipes having vertical tubes affixed the whole of the tubes of one row may be upflow tubes and the next row of the next transverse box or pipe the downflow for the water, and so on alternately, or by the shift of the valves 60 two of such transverse boxes and two rows of vertical tubes may be for upflow of water and the next transverse boxes or pipes and vertical tubes connecting them be for the downflow of the water, and so on in rows 65 transversely alone or in conjunction with other vertical tubes of the lower or of the upper valve box or pipe. Said valve boxes or pipes can be arranged at diametrically opposite corners of a stack of boxes or pipes 70 and tubes, and the connection between one set or series of tubes may be by branch pipes, which may be arranged according to any desired arrangement for the flow or passage of 75 water.

80 My invention will be more fully understood by reference to the annexed drawings, in which—

Figure 1 shows in sectional elevation top and bottom boxes or pipes provided with internal ribs and with valves on rods set in position for water to flow up all the tubes simultaneously and to the upper box and away through the outlet. Fig. 2 represents in vertical section the same boxes or pipes and 85 tubes with the valves moved along for the supply-water to flow up the first tube and down the next tubes, and so on in succession to the outlet; Fig. 3, a similar vertical sectional elevation of the same boxes or pipes 90 and tubes with the valves moved for the water to flow up the first two tubes and down the next two tubes, and so on to the outlet orifice, as indicated by the arrows; Fig. 4, a sectional elevation similar to Fig. 1, except 95 that the ribs in the boxes or pipes are of about three-quarter segments of a circle only, the other fourth being of the box or pipe itself, on which the valves and rods are supported 100

between the end caps of the boxes or pipes; Fig. 5, a sectional plan of lower and upper boxes or pipes having the valves arranged for single-tube flow into horizontal valveless boxes or pipes set transversely, which have branches for vertical tubes, all the tubes of each transverse row being alternately for up-flow and downflow in succession by the arrangement of the valves in the upper box and in the lower box, respectively; Fig. 6, a side elevation, partly in section, of a lower valve box or pipe, lower transverse valveless boxes or pipes, upper valveless boxes or pipes with vertical tubes connecting, and upper valve box or pipe for return of water down each alternate row of tubes, of which there may be any number to suit the extent of capacity available for fitting them. This view is taken through the lines *x x* of Fig. 7. Fig. 7 is an end elevation of lower and upper boxes arranged transversely and provided with vertical tubes for flow from and to the valve-containing pipes, these being at diametrically opposite portions of the structure, as before explained.

Similar letters of reference in the several figures indicate the same parts.

A is the water-inlet pipe; B, lower box or pipe; C, vertical tubes set in sockets D of the lower box B; E, upper box or pipe, with sockets F for upper ends of tubes C; G, valves in lower box or pipe; H, valves in upper box or pipe, said valves G H being on rods I J, operable by hand-wheels K L, as desired. The rods I J are screw-threaded near one end and work in threaded sockets M N of the inner ends of the boxes or pipes B and E, where each has a gland P to make the joint watertight, the opposite or outer ends of the rods being in cup-caps Q of the ends.

R are ribs in the boxes or pipes B E, into which the valves can be moved when the hand-wheels K L are turned to close some of the passages and to open others, according to the desired direction of flow.

S is the outlet for the heated water.

T is the blow-off opening in the lower box or pipe in relation to each or to a series of vertical tubes, or one blow-off can be common to all the vertical tubes.

U U are lower transverse boxes or pipes, connected at right angles by sockets V V to the lower valve box or pipe B, and C C are vertical tubes therefrom.

W W are the upper transverse boxes, connected by sockets X X to the vertical pipes C and also by sockets Y Y with the upper valve-box E.

In all the figures I have shown that the supply-water enters at the lower valve box or pipe; but it can be entered at the outlet-orifice S, and in that case the water would flow down the first vertical tube and then rise up the other or others, according to the disposition of the valves in the valve boxes or pipes.

What I claim, and desire to secure by Letters Patent, is—

The combination, in a heating apparatus, of vertical tubes C, upper and lower horizontal pipes E and B connected, respectively, with the upper and lower ends of said tubes and provided internally, in juxtaposition to, and at points between the ends of the vertical tubes, with internal ribs R constituting valve-seats, lengthwise-movable rods J and I, located in the horizontal pipes, and valves H and G, each rod having a series of attached valves located, respectively, between two of the said valve-seat ribs, and some of the valves constructed and arranged, respectively, to close against either one of two adjacent valve-seat ribs to change the direction of the flow of the supply-water, substantially as and for the purposes described.

In testimony whereof I have hereunto set my hand in presence of two subscribing witnesses.

EDWARD GREEN.

Witnesses:

ALFRED PROCTER,

GEORGE WILLIAM CURRY.
